UNITED STATES PATENT OFFICE.

SAMUEL BARUCH, OF NEW YORK, N. Y.

BOX-STRAP SEAL.

1,424,976.

Specification of Letters Patent. Patented Aug. 8, 1922.

Application filed February 25, 1921. Serial No. 447,892.

To all whom it may concern:

Be it known that I, SAMUEL BARUCH, a citizen of the United States, and resident of New York, in the county of New York, State of New York, have invented certain new and useful Improvements in Box-Strap Seals, of which the following is a specification.

This invention is an improved sealing device adapted for use in connecting strap ends such as are commonly used in connection with a box to prevent the box from being opened by unauthorized persons or to leave tell-tale evidence of the fact that the box has been opened. In my improved construction a tubular member is employed, into or through which the ends of the strap may be extended, portions of one wall of the tube being adapted to be deformed or bent into locking engagement with the strap so as to normally prevent the withdrawal of the strap therefrom.

As the important feature of my invention, I provide two or more annular upstanding beads in the upper or outer wall of the tube and encircling the portions which are to be bent or deformed into locking engagement with the strap. By means of a special tool, all of the portion encircled by each bead may be forced downwardly into or through the strap so that the bent portion will lie substantially tangential to the bead and without deforming or mutilating the latter. If the outer wall of the tube be pried or forced away from the strap end so as to permit the withdrawal of the latter, it will not be possible to again force the parts back into the original sealed condition without mutilating or otherwise deforming the bead so as to leave tell-tale evidence of the fact that the seal has been tampered with. As the deformed portion has been bent from a position at an angle to the side of the bead to a position tangential thereto, any attempt to bend the deformed portion back to its original position will cause a bending at some other point than at the point where the original bending took place, and a deforming of the bead will result. Any attempt to force the deformed portion back into the strap by hammering will also tend to flatten or mutilate the bead. The bead forms a well defined boundary for the deformed portion, and of definite diameter so that the parts cannot be resealed by forcing the metal wall farther into the strap to

destroy evidence of tampering as would be the case were the bead omitted.

In the accompanying drawings,

Figure 1 is a perspective view of a tubular member embodying my invention,

Figure 2 is a central longitudinal section showing the device sealed to one strap end, and

Figure 3 is a transverse section on the line 3—3 of Figure 2 on a greatly enlarged scale.

In the specific form illustrated I employ a tubular member formed of sheet metal, and formed with opposite walls 10 and 11 disposed substantially parallel and spaced apart to a distance permitting of the convenient insertion of a strap end at each end of the tubular member to spaced, abutting or overlapping position. The drawing illustrates a device on a somewhat larger scale than would ordinarily be used in practice as the device may be made in such size as to conveniently receive metal strap ends 12 and 13 of a width in the neighborhood of three-eighths or one half an inch. Obviously the device may be made to receive wider or narrower straps. Although the tubular member may be made of seamless tubing, I have shown it as having a seam 14 which may be in either the upper or lower wall, but preferably in the wall intended to lie adjacent to the wall of the box or other device in connection with which the sealing straps are used.

The outer wall 10 of the box has two or more annular outwardly extending beads 15 each encircling a flat portion 16 in the plane of the remainder of the wall. This encircled portion preferably has a central aperture 17. When it is desired to employ the device for sealing together a pair of strap ends, these ends are inserted into opposite ends of the tubular member, either as shown in Figure 2, or so as to overlap, and the portion 16 is forced downwardly into or through the strap by means of a special tool, as shown in Figure 3. This tool 18 is provided with a flat portion 19 adapted to engage with the outer surface of the tubular member, an annular groove 20 adapted to receive the bead 15, and a central conical projection 21 extending tangential to the groove 20. The point of the tool is placed in the aperture 17, and by pressure or blows the portion 16 encircled by the bead, is forced downwardly to substantially the tapered annular

form as shown at 16^a in Figure 3. The tool and this portion of the wall of the tube also serve to perforate and deform the strap, and the lower wall of the tube. It will be understood that Figure 3 illustrates a very much enlarged and possibly somewhat idealized bending of this portion. The deformed portion 16^a, as well as the portion 22 of the strap, prevents the withdrawal of the strap. 10 If any thin instrument be inserted between the upper wall of the tube and the strap in an effort to bend the portion 16^a back to its original form, it will result in a mutilation or deformation of the bead, and any attempt 15 to bend the portions back to the position shown in Figure 2 will also result in a bending, flattening or other mutilation of the bead. Thus the use of this bead in its relationship to the portion to be deformed insures freedom from tampering and the certain indication of tampering should the latter occur.

It will of course be evident that the tubular member may serve not only to connect and seal the strap ends, but may also be used as a name-plate by embossing the outer wall with the name of the shipper, or with any other identification mark. For instance the devices may bear embossed serial numbers, so that the shipper may notify the consignee of the numbers of the seals on the package, and thus prevent the entire removal of the seal and substitution of a new one by a person who has broken into the package during transit.

I have described my device as used for connecting the strap ends used for encircling and sealing boxes, but it will of course

be evident that it may be used for sealing or connecting the ends of any other flat strap-like members used for other purposes. Obviously the metal of the tube may be such that nails may be driven directly through the tubular member and strap when the parts are in position, to hold them rigidly 45 in position on the box.

Having thus described my invention, what I claim as new and desire to secure by Letters Patent is:

1. A seal for strap ends including a tubular member adapted to receive the strap ends, and having its outer and inner walls, each provided with a portion adapted to be deformed into locking engagement with the strap, said outer wall having an annular 55 outwardly extending bead encircling the portion thereof to be deformed.

2. A seal for strap ends including a tubular member adapted to receive the strap ends, and having its outer surface provided 60 with a portion adapted to be deformed into locking engagement with the strap and a bead encircling and defining the limits of said first mentioned portion.

3. A device of the class described, including a tubular member having one wall provided with an outwardly extending annular bead encircling a portion normally lying in the plane of the remainder of the wall, the portion encircled by said bead being adapted 70 to be deformed so as to lie substantially tangential to the surface of the bead.

Signed at New York in the county of New York and State of New York this 16th day of February, A. D. 1921.

SAMUEL BARUCH.
